UNITED STATES PATENT OFFICE.

ARNDT M. KRAUSE, OF CHICAGO, ILLINOIS, ASSIGNOR TO CENTRAL SCIENTIFIC COMPANY, OF CHICAGO, ILLINOIS, A CORPORATION OF ILLINOIS.

MERCURIAL BAROMETER.

1,353,482.

Specification of Letters Patent. Patented Sept. 21, 1920.

Application filed May 23, 1918. Serial No. 236,078.

To all whom it may concern:

Be it known that I, ARNDT M. KRAUSE, a citizen of the United States, residing at Chicago, in the county of Cook and State 5 of Illinois, have invented certain new and useful Improvements in Mercurial Barometers, of which the following is a specification.

This invention relates to mercurial barometers and has for its object the provision of a barometer in which the column is separate from the cistern and is connected thereto by means which insures easy adjustment in use and safety in transportation.

15 A further object of my invention is the provision of a barometer in which the cistern is bodily adjustable relatively to the column.

Further objects and advantages of my invention reside in the provision of means for protecting the glass cistern and in the various combinations hereinafter described as will be better understood by reference to the following specification when read in connection with the accompanying drawing illustrating the preferred embodiments thereof, in which—

Figure 1 is an elevation of a barometer according to my invention with parts broken 30 away for better illustration;

Fig. 2 is a vertical section through the barometer;

Fig. 3 is a view in perspective of the lower end of the barometer;

35 Fig. 4 is a section on the line 4—4 of Fig. 1;

Fig. 5 is an elevation of a slightly different form of the barometer;

Fig. 6 is an enlarged sectional view 40 through the cistern;

Fig. 7 is a view in perspective of the column and cistern, and

Fig. 8 is a detail in perspective of the metal tube surrounding the column and the 45 shield for the cistern.

Referring to Figs. 1 to 4 of the drawing, 5 indicates the column consisting of a glass tube of uniform bore and sealed at its upper end in the usual manner. The lower end of the column 5 is disposed within and secured to a collar 6 of suitable material, in the present instance preferably Monel metal. The extreme lower end 7 of the column 5 is

preferably constricted as indicated in the drawing.

A cistern 8, preferably of glass, is connected at its upper end preferably by means of plaster of Paris 9 to an annular member 10 which is mounted on and threadedly engages the collar 6. A washer 11 of felt or other suitable material is disposed on the upper surface of the annular member 10 with its inner edge engaging the threads on the collar 6 to prevent the escape of mercury 12 from, while permitting air to enter and leave, the cistern. The lower end of the cistern 8 is inclosed within a metal shell 13, preferably of brass, provided with a knurled end 14 forming a head to protect the cistern to facilitate its adjustment. The space between the shell 13 and the cistern is filled with plaster of Paris 15 which secures the shell and cistern in assembled relation. The usual ivory point 16 is mounted in the lower end of the collar 6 to engage the surface of the mercury. A cylindrical shield 17, preferably of brass, is secured to the collar 6 and telescopes with the shell 13 to inclose the cistern and lower end of the collar. Windows 18 are provided in opposite sides 70 of the cylinder 17 through which the contact of the ivory point 16 with the mercury may be observed.

A metal tube 19 which in the present embodiment is hexagonal in form, surrounds 85 the column 5 throughout its length and is provided at its upper end with a cap 20 in which a swivel hanger 21 is mounted. The tube 19 is secured at its lower end to the collar 6 by screws 22 and at its upper end to the cap 20 by screws 23. Preferably, an annular member 24 of cork or other suitable material is disposed within the tube 19 adjacent its upper end to receive the upper end of the column 5.

The tube 19 is provided with oppositely disposed sight openings 25 and the usual scales 26 are secured to the tube 19 by screws 27. A vernier 28 is mounted between the adjacent edges of the scales 26 and is held in assembled relation therewith by a spring 29 disposed within the tube 19 with its ends in engagement with the inner faces of the walls thereof. The spring 29 is mounted on a pin 30 which extends through the vernier 100 and is provided with a knob 31 adapted to

be grasped by the operator to move the vernier along the scales 26. The spring 29 provides frictional contact which holds the vernier in any adjusted position and permits easy adjustment thereof.

As will be readily understood the instrument is adjusted by grasping the knurled end 14 and rotating the cistern on the threaded collar 6, until the ivory point 16 touches the surface of the mercury 12. This adjustment is very simple and it will be noted that the entire cistern is adjusted relative to the column 5, thus obviating the necessity of providing flexible bags or pistons as has been usual in well known types of barometers now in common use.

Referring to Figs. 5 to 8 of the drawing 35 indicates the column consisting of a glass tube of uniform bore and sealed at its upper end in the usual manner. The lower end of the column 35 is disposed within a collar 36 of suitable material such as fiber of vulcanite. The extreme lower end 37 of the column is constricted to permit the insertion of cement 38 which securely fastens the collar to the column.

A cistern 39 preferably of glass is connected at its upper edge by cement 40 to an annular member 41 which is mounted on and threadedly engages the collar 36. The lower end of the cistern 39 is provided with a head 42. A washer 43 of felt or other suitable material is disposed in a suitable recess in the top of the annular member 41. The usual ivory point 45 is mounted in the lower end of the collar 36 to engage the surface of the mercury.

A metal tube 46, hexagonal in form, surrounds the column 35 throughout its length 40 and is provided at its upper end with a swivel hanger and cap 47. The lower end of the tube 46 is provided with a plurality of tongues 48, the inturned ends of which are adapted to engage a groove 49 in the upper end of the collar 36 above a flange 50 thereon. The tongues 48 bend outwardly above the inturned ends and a shield 51 is slidably mounted on the tube and adapted when forced to the position indicated in Fig. 6 to move the tongues 48 inwardly causing the inturned ends of the latter to engage the groove 49 and firmly lock the tube to the collar 36. The shield 51 in addition to its locking function surrounds the collar 36 and the upper portion of the cistern 39 giving a finished appearance to the instrument and protecting its parts.

The tube 46 is provided with oppositely disposed sight opening 46' and the usual scale 52 and vernier 53 are mounted on the tube adjacent the openings to permit reading of the instrument. The usual thermometer 54 is also secured to the tube 46.

As will be readily understood the instrument is adjusted as in the preceding embodiment by grasping the head 42 and rotating the cistern on the threaded collar 36 until the ivory point 45 touches the surface of the mercury 44. This adjustment is very simple and it will be noted that the entire 70 cistern is adjusted relative to the column 35, thus obviating the necessity of providing flexible bags or pistons as has been usual in well known types of barometers now in common use.

My invention greatly improves the mechanical construction of the particular type of barometers to which it relates and facilitates shipment of the barometer without danger of breakage. It has been 80 customary in the past to support the cistern on the column and due to the weight of the mercury much loss has been occasioned by breakage in shipment. I have overcome this by supporting the cistern independent of the column and protecting it so that loss by breakage has been reduced to a minimum. For the purpose of shipment the cistern is adjusted to the limit of its upward movement in which position 90 it is protected by the shield 17. For actual use the cistern can be conveniently adjusted relative to the column as required and the liability of wear on the cistern as in the case of the flexible bags heretofore employed, is entirely avoided.

I am aware that changes in the form, construction and arrangement of parts of my invention may be made without departing from the spirit or sacrificing the advantages 100 thereof and I reserve the right to make all such changes as fairly fall within the spirit and scope of the following claims.

I claim:

1. A mercurial barometer comprising a 105 column, a collar on the column adjacent the lower end thereof and having a threaded portion, a shield on the collar surrounding said threaded portion, a cistern inclosing the lower end of the column, an annular member supporting said cistern and adjustably mounted on the threaded portion of the collar within said shield, and a protecting shell on the lower portion of the cistern co-operating with the shield to inclose and protect the cistern.

2. A mercurial barometer comprising a column, a collar on the column adjacent the lower end thereof and having a threaded portion, a shield on the collar surrounding 120 said threaded portion, a cistern inclosing the lower end of the column, an annular member supporting said cistern and adjustably mounted on the threaded portion of said collar within said shield, and a shell inclosing the lower portion of the cistern and telescopingly engaging the shield.

3. A mercurial barometer comprising a column, a collar on the column adjacent the lower end thereof, and having a depending 130

threaded portion, a cistern inclosing the lower end of the column, an annular member supporting the cistern and adjustably mounted on the threaded portion of the collar, a tube surrounding the column above the collar and having a plurality of tongues at its lower end to engage the collar, and a shield inclosing said annular member and

extending down approximately to the bottom of the threaded portion of the collar 10 and engaging said tongues to hold them in operative engagement with the collar.

ARNDT M. KRAUSE.
